(57) **CLAIM**

The ornamental design for a video magnifier, as shown and described.

DESCRIPTION

FIG. 1 is a front elevational view of a video magnifier showing our new design;

FIG. 2 is a rear elevational view thereof;

FIG. 3 is a top plan view thereof;

FIG. 4 is a right side elevational view thereof;

FIG. 5 is a left side elevational view thereof;

FIG. 6 is a perspective view taken from the front, top and right side of the video magnifier; and,

FIG. 7 is a perspective view taken from the front, top and right side of the video magnifier thereof, with the monitor shown in broken line for the purpose of illustrating only and forms no part of the claimed design.
